ATTORNEY

UNITED STATES PATENT OFFICE

GEORGE H. ROGERS, JR., OF OAK PARK, ILLINOIS

COLLAPSIBLE SUPPORT FOR BABY SWINGS

Application filed September 5, 1929. Serial No. 390,483.

This invention relates to improvements in collapsible supports, particularly for baby swings or that type of spring supported seat for infants which results in a gentle up and down motion and also a swinging movement when the child is placed therein.

One of the particular objects of this invention is the provision of a collapsible support for baby swings or the like which will positively and reliably support an ordinary baby swing with an infant therein without any danger of collapse, and which, furthermore, may be folded up into a small compass and put away when not in use.

Another and further important object of this invention is the provision of a support for baby swings or the like which is adapted to be used in an ordinary household or apartment, and which will eliminate the necessity of suspending the ordinary baby swing in a doorway or passageway as has heretofore been done, and which results in considerable inconvenience.

Still another and further important object of this invention is the provision of a novel and simple, yet efficient method of connecting the upper ends of a plurality of supporting legs which allows of a universal movement and further admits of the co-operation therewith of suitable supporting means for any object adapted to be suspended from said support.

Other and further important objects of the invention will be apparent from the disclosures in the accompanying drawing and following specification.

The invention, in a preferred form, is illustrated in the drawing and hereinafter more fully described.

40 In the drawing:

Figure 1 is a vertical perspective view of the improved baby swing and support of this invention.

Figure 2 is a detail view illustrating the novel means of connecting the upper ends of the supports for universal movement about each other and also illustrates the adaptation of a suitable hanger for the baby swing to the support.

50 Figure 3 is a detail view somewhat simi-

lar to Figure 2, but illustrating more fully the swing supporting means.

Figure 4 is a detail view illustrating the method of connecting the retaining ring to the upper ends of the supports, as shown in Figure 1.

As shown in the drawing:

The reference numeral 10 indicates generally an ordinary baby swing, many modifications of which are now on the market, and which is suspended by means of a helical spring or the like 12 which admits of a gentle up and down motion when the swing is in use.

As best shown in Figure 1, the improved support of this invention comprises a plurality of supporting legs 14 or the like, which in the present case are three in number, to form a tripod, but which obviously may be increased to four or more if it is necessary or desired.

Each leg 14 is preferably provided with a suitable rubber foot 16 whereby slippage is avoided and adjacent the upper end of each leg 14 is affixed a length of chain or strong cord 20 whereby any undue spreading of the legs is avoided.

In order that the legs or supports 14 be positively fastened together at their upper ends yet at the same time adapted for practically a universal movement with respect to each other a suitable retaining element in the form of a ring 22 is provided as best shown in Figure 2, and which is of a circumference sufficient to encompass the upper ends or heads of all the legs 14 while at the same time allowing of a suitable amount of free motion of the legs with respect to each other. In order that the ring 22 be securely maintained in desired position with respect to the upper ends of the supports or legs 14 each leg has the ring attached thereto by means of a suitable eyebolt or the like as illustrated at 34 in Figures 2 and 4. These eyebolts may be mounted on the heads of the supports 14 in any suitable manner, but at best illustrated in Figure 4, a preferable method of mounting is herein indicated.

In Figure 4 the eyebolt 34 having the ring 22 passing therethrough is fitted with a shank 100

26 of a length sufficient to pass almost through the diameter of the head of the support 14.

As indicated in Figure 2, suitable means must be provided for supporting the hanger or chain 40 of the swing itself and in one instance this is accomplished by means of a suitable bolt or other fitting 44 passing through the upper end of one of the supporting legs 14, and to which is adapted to be fitted the upper end of the chain 40. When the device is set up the chain 40 is automatically pulled into position by the weight of the swing 10 and its contents and thereafter materially assists in maintaining any desired relation between the upper ends of the supports 14.

It will be obvious that herein is provided a collapsible support for baby swings, the legs of which are adapted for universal movement about its head and which can be conveniently and quickly set up in any desired location, and which may further be just as conveniently and quickly taken down and stored away. The collapsibility of the device into a very small compass enables it to be readily transported from place to place whereby its uses and adaptability are multiplied. Although particularly designed as a baby swing support it may obviously be used for other purposes if desired.

I am aware that many changes may be made and numerous details of construction varied throughout a wide range without departing from the principles of this invention, and I therefore do not purpose limiting the patent granted hereon otherwise than as necessitated by the prior art.

I claim as my invention:

40 A collapsible support for baby swings, including a plurality of supporting legs mounted for loose movement about a retaining head, said retaining head comprising a ring loosely surrounding the upper ends of said supporting legs and a fastening element on each leg through which said ring passes, each of said fastening elements comprising an eye-bolt, and an additional supporting element adapted to suspend said baby swing 45 from approximately the center of said head, said means comprising a bolt passing through the upper end of one of said supporting legs.

55 In testimony whereof I affix my signature.
GEORGE H. ROGERS, JR.
